UNITED STATES PATENT OFFICE.

FORD W. HARRIS, OF WILKINSBURG, PENNSYLVANIA, ASSIGNOR, BY MESNE ASSIGNMENTS, TO WESTINGHOUSE ELECTRIC & MANUFACTURING COMPANY, OF EAST PITTSBURG, PENNSYLVANIA, A CORPORATION OF PENNSYLVANIA.

CIRCUIT-INTERRUPTER.

1,003,044.

Specification of Letters Patent. Patented Sept. 12, 1911.

Application filed May 9, 1908. Serial No. 431,818.

To all whom it may concern:

Be it known that I, FORD W. HARRIS, a citizen of the United States, and a resident of Wilkinsburg, in the county of Allegheny and State of Pennsylvania, have invented a new and useful Improvement in Circuit-Interrupters, of which the following is a specification.

My invention relates to circuit interrupters and it has special reference to such interrupters as are adapted for relatively high voltage circuits and for out-door or manhole service.

The object of my invention is to provide a device of the class above indicated that shall be simple and durable in construction and that shall be specially economical and compact.

My invention is illustrated in the accompanying drawings in which—

Figure 1 is an end elevation, and Fig. 2 a front elevation of a circuit interrupter constructed in accordance therewith, the inclosing casing being in section in both figures in order to disclose the operating mechanism, Figs. 3, 4, 5, 6, 7, and 8 are detail views of the operating parts of the device.

Referring to the drawings, the device here illustrated comprises an inclosing casing 1, which consists of a supporting frame 2, a fluid-containing tank 3 and a cover 4; an insulating plate or slab 5, stationary contact members 6 and 7, a movable contact member 8, an operating mechanism and an electro-responsive releasing mechanism.

The operating mechanism comprises a main shaft 11 which is journaled in bearings 12 and 13 formed in opposite side walls of the supporting frame 2, an operating lever 14, which is rotatably mounted on the shaft 11 substantially at its middle point, and at the middle point of the lever, a stationary cross strip 15 which is substantially parallel to the shaft 11 and is directly above it and helical springs 16 and 17 that are coiled about the shaft 11 between the lever 14 and the bearings 12 and 13. One end of the shaft 11 extends through the wall of the frame 2 and is provided with an operating handle lever 18 by which rotative movement of the shaft in either direction may be ef-

fected. The ends of the spring 16 extend upwardly in substantially vertical lines, one on one side of the strip 15 and one on the other. The outer end of the spring 16 is also engaged by an arm 19 of a dog 20 that is fixed to the shaft 11 adjacent to the bearing 12, the said arm 19 and strip 15 being on the same side of the spring end. A dog 21, which is located between the spring 16 and the lever 14, has a projection 22, that engages the inner end of the spring on the same side as that engaged by the strip 15. The arrangement of parts is such that the spring tends to return the shaft 11 to a predetermined central or intermediate position when it is moved therefrom in either direction. The outer end of the spring 17 engages the strip 15 but its inner end is so engaged by a projection 23 of the lever 14 that it tends to so move the lever 14 as to cause the movable contact members to be separated from the stationary contact members. The dog 21 is also provided with a downwardly extending projection 24, which is adapted to engage a lug 25 on the side of the lever 14 when the shaft 11 is actuated in one direction and to engage the outer end of an arm or tripping lever 26 when the shaft 11 is actuated in the opposite direction. The arm 26 forms a part of a bell crank lever which is bifurcated and is fulcrumed upon a pin 28 that projects laterally through the lever 14 near one end. The bell crank lever comprises a latch projection 29 and tripping levers 26 and 30.

The electro-responsive release mechanism may be constructed in any suitable manner and comprises, as illustrated in the drawings, a magnet coil 34, a stationary core member 31, a movable core member 32 and a hammer rod 33 which is secured to the movable member and extends loosely through a hole in the stationary member. This hammer rod is adapted to engage the outer end of the lever 30 when the coil 34 is energized.

The contact members, which form no part of my present invention and may comprise, in general, cylindrical blocks of conducting material, two of which constitute the stationary members and are secured to the plate 5 and two others which are parts of

the movable member and are resiliently secured to opposite ends of a cross bar 35 and are electrically connected together by a flexible conductor 36 and the coil 34, which 5 is included in circuit therewith. The cross bar 35 is secured to the lower end of a connecting link 37 which is interposed between one end of the lever 14 and an intermediate point in the bar. The rotative movements 10 of the lever 14 about the shaft 11 are limited by projections 38 and 39 on the supporting frame 2.

The operation of the circuit interrupter is as follows: Assuming that one end of the 15 lever 14 engages projection 38, the stationary and movable contact members being then separated to a maximum degree, if it is desired to close the circuit controlled by the interrupter, the handle lever 18 and the shaft 11 are turned in a clockwise direction to bring the projection 24, of the dog 21, into engagement with the lug 25 on the lever 14 and, as the rotative movement is 20 continued, the lever 14 will be so moved 25 as to raise the movable contact member 8 into engagement with the stationary contact members 6 and 7. The above specified movement of the shaft is opposed by the spring 16 and that of the lever 14 is opposed by the spring 17 but the lever is held 30 in this closed circuit position by the engagement of the latch 29 with a projection 40 on the supporting frame 2. The handle lever will be returned to its intermediate position as soon as it is released by the attendant. If the current traversing the coil 34 exceeds a predetermined amount, the movable core member 32 will be actuated and the rod 33 will strike the lever 30 and cause a 35 slight rotative movement of the bell crank 27 upon the pin 28 to release the latch 29 from the projection 40. A similar action may be effected by an attendant by rotating the handle 18 and the shaft 11 in a counter-clockwise direction whereby the projection 40 of the spring dog 21 is moved into engagement with the end of the arm 26 of the bell crank lever. As soon as the latch is released, the spring 17 will cause a rapid 45 movement of the movable contact member 30 away from the stationary members and an interruption of the circuit will result.

The tank 3 may be filled with oil or other suitable insulating fluid in which it is desired to immerse the contact members and the coil which forms a part of the release mechanism.

From the foregoing description it will be understood by those familiar with the art 60 that a positive operation of the device is always effected while the operating mechanism is specially simple and compact.

Inasmuch as various structural modifications may be effected in the device illustrated 65 without departing from the spirit of my

invention, I desire that only such limitations shall be imposed as are indicated in the appended claims.

I claim as my invention:

1. In a circuit breaker, the combination 70 with a stationary contact member, an operating lever, a shaft upon which said lever is fulcrumed and from which it projects in opposite directions, and springs for respectively returning the shaft and the lever to 75 open-circuit positions, of a movable contact member pivotally suspended from one end of said lever, a latch pivotally suspended from the other end of said lever; and means dependent upon a rotative movement of the 80 shaft in one direction for tripping the latch.

2. In a circuit-breaker, the combination 85 with a stationary contact member, a shaft, and an operating handle secured to one end of the shaft, of an operating lever fulcrumed at an intermediate point in its length, springs coiled about the shaft for respectively returning the shaft and the lever to open-circuit positions, a link pivotally suspended from one end of the lever, a contact 90 member to which said link is attached, a latch pivotally suspended from the opposite end of the lever and means dependent upon a predetermined movement of said shaft for tripping the latch. 95

3. In a circuit-breaker, the combination 100 with a rotatively movable shaft and an operating lever fulcrumed upon the shaft at an intermediate point in its length, of a movable contact member operatively connected 105 to one end of the lever, stationary contact members coöperating therewith, a latch member pivotally suspended from the opposite end of the lever for holding the contact members in engagement with each other, a 110 helical spring coiled about the shaft and opposing rotative movement of the lever in one direction, a second helical spring coiled about the shaft and opposing rotative movement of the shaft in either direction and 115 means dependent upon rotative movement of the shaft in one direction for closing the circuit-breaker and means dependent upon rotative movement of the shaft in the opposite direction for tripping the latch member. 115

4. In a circuit-breaker, the combination 120 with stationary and movable contact members, of an operating lever fulcrumed upon a horizontal axis and projecting therefrom in opposite directions, a link connecting the 125 movable contact member to one end of the lever, an operating handle, resilient means for returning the lever to open-circuit position, a latch member pivotally suspended from the opposite end of the lever, an automatic latch-tripping means, and a means dependent upon a predetermined movement of the operating handle for tripping the latch.

5. In a circuit-breaker, the combination 130 with stationary and movable contact mem-

bers, a rotatively movable shaft mounted in a horizontal plane and an operating lever fulcrumed upon the shaft, of a link connecting the movable contact member to one end 5 of the lever, a helical spring coiled about the shaft and opposing rotative movement of the lever in one direction, a latch member pivotally suspended from the opposite end of the lever for holding the contact members 10 in engagement with each other, electro-responsive means for tripping the latch and

other means dependent upon rotative movement of the shaft in one direction for tripping the latch.

In testimony whereof, I have hereunto 15 subscribed my name this 30th day of April, 1908.

FORD W. HARRIS.
